ABSTRACT

The octane number of paraffinic gasoline blending components may be increased by (1) cyclizing the n-paraffins with hydrogen under reforming conditions in the presence of a catalyst prepared by depositing a noble metal on magnesium oxide and mixing the resulting noble metal-magnesia into an alumina gel matrix, and (2) subjecting the cyclized component to conventional catalytic reforming.

UPGRADING OF PARAFFINIC GASOLINE
BLENDING COMPONENTS BY CYCLIZATION
WITH A PLATINUM/MAGNESIUM OXIDE
ALUMINA MATRIX CATALYST

BACKGROUND OF THE INVENTION

Reforming operations, where hydrocarbon fractions such as naphthas, raffinates and condensates, are treated to improve octane numbers are well known in the petroleum processing art. One of the principal results of reforming operation is the raising of octane numbers, particularly for use in lead free gasolines. The hydrocarbon fractions which are improved by the reforming operation are composed predominantly of normal and slightly branched paraffinic hydrocarbons and naphthenic hydrocarbons together with small amounts of aromatic hydrocarbons. During reforming, a multitude of reactions take place, including isomerization, aromatization, dehydrogenation, cyclization, etc., to yield a product having an increased content of aromatics and highly branched paraffins. Thus, in the reforming operation, it is desired to dehydrogenate the naphthenic hydrocarbons to produce aromatics, to cyclize the straight chain paraffinic hydrocarbons to form aromatics, and to isomerize the normal and slightly branched paraffins to yield highly branched chain paraffins. Additionally, under the appropriate circumstances, it is also desired to effect a controlled type of cracking which is both selective in quality and quantity; i.e., the cracked paraffinic products desirably have six or more carbon atoms.

Normal and slightly branched chain paraffinic hydrocarbons of the type contained in reforming feedstock fractions have relatively low octane ratings. Highly branched chain paraffinic hydrocarbons, on the other hand, are characterized by high octane ratings. Thus, one objective of the reforming operation is to effect isomerization of the normal and slightly branched chain paraffins to more highly branched chain paraffins. Also, since aromatic hydrocarbons have much higher octane ratings than naphthenic hydrocarbons, it is also an objective of reforming simultaneously to produce aromatics in good yield. The production of aromatic hydrocarbons during reforming is effected by dehydrogenation of the naphthenic hydrocarbons and dehydrocyclization of the paraffinic hydrocarbons. Aromatic hydrocarbons are also produced by isomerization of alkyl cyclopentanes to cyclohexanes, which thereafter undergo dehydrogenation to form the desired aromatics. A convenient measure of the effectiveness of a reforming operation is based on a yield-octane relationship. It is desired in reforming to maximize this relationship, i.e., high depentanized yields for any given octane

Certain hydrocarbon fractions which fall within the boiling point range for gasoline blending components are composed principally of normal and slightly branched chain paraffins. These paraffinic stocks are very low in octane number and therefore, unless they are subjected to a reforming operation, they are not suitable for inclusion in lead free gasolines. Reforming of these blending components, however, has been somewhat less than satisfactory, owing principally to undesired cracking reactions which occur in conventional reforming operations. This cracking, which produces mainly butanes and lighter hydrocarbons, results in a significant loss of gasoline product.

It is therefore a principal object of this invention to develop a method for reforming paraffinic gasoline blending components in order to increase their octane number.

- 5 It is another object of this invention to develop a method for reforming these gasoline blending components without encountering a substantial loss in product volume as a result of conversions to butanes and lighter hydrocarbons.
- 10 A further object of this invention is to develop an effective catalyst for the upgrading of highly paraffinic gasoline blending components.

SUMMARY OF THE INVENTION

- 15 According to this invention, paraffinic gasoline blending components are upgraded by a two step process involving (1) cyclization of paraffins, and (2) catalytic reforming of the cyclized product in the usual manner. The cyclization step is accomplished by contacting the paraffinic gasoline blending component with hydrogen in the presence of a novel catalyst prepared by depositing a noble metal on magnesium oxide and then mixing this noble metal-magnesia into an alumina matrix.

25 DISCUSSION OF THE PRIOR ART

Most of the multi-step reforming processes heretofore known disclose that the cyclization reactions take place in the final, rather than the initial stages of the reforming process. The instant invention is characterized by the fact that the cyclization reactions take place prior to the other reforming reactions, e.g., dehydrogenation and isomerization. It is further characterized by the use of a novel catalyst.

- 30 U.S. Pat. No. 3,395,094, issued to Weisz, discloses catalysts which are typically used in multi-step reforming operations. A two step operation is disclosed in which the catalyst of the first step is platinum or another noble metal deposited on alumina. Combined with the alumina, there may be other components such as magnesium oxide. There is no indication, however, in this patent or in other prior art relating to similar reforming catalysts that the noble metal should first be deposited on magnesium oxide alone and that the magnesium oxide-noble metal mixture then be deposited on or mixed with alumina.

- 35 U.S. Pat. No. 3,654,184, issued to McCallister et al, discloses a platinum/germanium oxide/alumina gel catalyst. A soluble platinum compound is combined with an aqueous solution of germanium oxide. A halogenated alumina gel is then impregnated with the combined solution. The disclosure is specific to the use of a germanium oxide solution; there is no indication that magnesium or any other metal may be used in place of the germanium and, further, there is no indication that the platinum may be deposited on a solid chemical rather than being mixed with a solution.

DETAILED DISCLOSURE OF THE INVENTION

- 40 The paraffinic gasoline blending component which constitutes the feedstock in the process of the instant invention is typically a hydrocarbon fraction boiling within the gasoline boiling range and having a paraffin content of from about 70 percent or higher, most of the paraffins being in straight chain or slightly branched compounds. Examples of suitable feedstocks are light straight run naphthas, raffinates and condensates. The paraffinic stock is cyclized by contacting with hydrogen

under reforming conditions with the novel catalyst of this invention. Said catalyst is prepared by depositing a noble metal on magnesium oxide and then mixing the resultant intermediate into an alumina matrix. The noble metal is, for example, palladium or platinum, with platinum being preferred. The deposition of the noble metal on the magnesium oxide is conveniently accomplished by impregnating magnesium oxide powder with a solution of the noble metal compound. Examples of such compounds include platinum chloride, chloroplatinic acid, ammonium chloroplatinate, dinitrodi amino platinum, palladium chloride, chloropalladic acid, and the like. When the noble metal is platinum, the preferred soluble platinum compound is chloroplatinic acid.

Additionally, the noble metal may be stabilized with a suitable metal selected from Groups IVA, VB, VIB, VIIB or VIII of the Periodic Table. Examples of such metals are: Group IVA: Ge, Sn, Pb; Group VB: V, Nb, Ta; Group VIB: Cr, Mo, W; Group VIIIB: Mn, Re; Group VIII: Fe, Ni, Co, Ru, Rh, Pd, Os, Ir and Pt. (Preferred metals are underlined.)

The magnesium oxide with the noble metal deposited on or impregnated is then, if necessary, dried prior to further processing. The dried impregnated magnesium powder is then mixed with an alumina gel which may contain up to about 2% silica. The alumina gel itself is prepared by methods well known in the art, for example, by dissolving aluminum sulfate in water and then adding concentrated ammonium hydroxide in order to precipitate aluminum hydroxide.

The cyclization step may take place under ordinary reforming conditions in a reactor normally used for reforming operations. The general and preferred operating conditions for this reaction are listed below in Table I.

TABLE I

Operating Condition	General Range	Preferred Range
Temperature, °F.	500-1100	700-1000
Pressure, psig	50-900	50-500
Gas Rate, SCFB	500-10000	1000-5000
Space Velocity, Vo/H ₂ /Vc	0.2-10.0	.5-8.0
Hydrogen Purity, mol%	50-100	80-100

This reaction cyclizes the paraffins into naphthenes and aromatics in very high depentanized yields. The cyclized paraffinic stock is then passed to a conventional catalytic reforming unit containing a conventional platinum or platinum bi-metallized reforming catalyst on an

alumina or alumina containing support. This second step is run according to methods well known in the art.

SPECIFIC EXAMPLES

The invention will be better understood by reference to the following specific examples which are included here for the purposes of illustration only and are not intended as limitations.

EXAMPLE I

Catalyst preparation

The catalyst of this example consists essentially of platinum (0.75 wt. %) impregnated magnesia powder in an alumina gel matrix.

MgO powder, 450 grams, was impregnated with 75 ml. of a chloroplatinic acid solution (0.05g Pt/cc, diluted to 200cc). The platinum impregnated magnesia powder was dried on the steam plate at a temperature of 130°-140°F.

The alumina gel was prepared by dissolving 490 grams of $Al_2(SO_4)_3 \cdot 18 H_2O$ in 5 liters of distilled water to which 300cc of concentrated NH_4OH was added to effect precipitation of $Al(OH)_3$. The alumina gel was washed 3 times with cold water and filtered to remove most of the sulfate. The Pt-MgO powder was then mixed with the alumina gel and passed through a Colloid Mill. This material was dried on the steam plate for a sufficient amount of time to remove moisture and obtain a good extrusion mix. The dried material was crushed using a mortar and pestle and sieved to -40 mesh.

The material was then extruded in a California Pellet Mill in the form of 1/16 inch pellets. The pellets were dried in air on the steam plate (130°-140°F.) for 8 hours at 300°F. in an oven followed by calcination for 2 hrs. at 1000°F. starting at 500°F. and raising the temperature 100°F. per hour. The average crush strength of the pellets was 8.0 pounds.

EXAMPLE II

In this Example, the catalyst prepared in Example I was used to cyclize a Udex raffinate. The raffinate was treated in three separate runs at temperatures of 850°, 900° and 950°F. For all runs, pressure was 50 psig, hydrogen rate was 6,000 SCFB and the liquid hourly space velocity (LHSV) is defined as the volume of liquid hydrocarbon charge per hour per volume of catalyst contained in the reaction zone. The product formed and their properties are set forth in the following Table II, which also sets forth the properties of the charge stock.

TABLE II

Run	A	B	C	Charge
Temperature, °F.	850	900	950	
Recovery, C ₅ ⁺ vol. %	98.98	94.91	91.63	
Product Quality				
Gravity, °API	56.0	54.2	53.0	59.6
RON, clear	63.0	66.1	73.3	42.0
FIA A	22		29.5	12.5
0	5.5		10.5	2.0
S	72.5		60.0	85.5
n-paraffins	—	13	14	
Mass SPEC, vol basis				
Paraffins	60.2	55.5	52.2	80.4
Monocycloparaffins	16.7	17.1	15.5	7.6
Dicycloparaffins	2.2	3.4	2.8	0.0
Tricycloparaffins	0.8	1.5	2.3	0.1
Alkylbenzenes	19.4	21.7	26.4	11.4
Indanes	0.7	0.8	0.8	0.4
Naphthalenes	0.0	0.0	0.0	0.0

These data indicate that a large percentage of the normal and isoparaffins present in the feedstock is converted to primarily cycloparaffins and aromatics. Furthermore, there is very little loss of C₅ and higher material to cracked products.

EXAMPLE III

In this example, the product produced at 850°F. in Example II and the raw raffinate charge stock were processed separately over a platinum on alumina catalyst in a conventional reforming operation. The characteristics of the catalyst used are as follows:

TABLE III

Pt 0.375 wt.-%	F 0.51 wt.-%	Cl 0.23 wt.-%	γ-alumina support

This conventional operation was carried out at 500 psig, 1.0 LHSV, 890°F. and at a hydrogen to hydrocarbon mol ratio of 6:1. The products produced from these two reforming operations and their properties are indicated in Table IV.

TABLE IV

Total (vol. = C ₄ –)	100.00	90.34	100.00
DB liquid data			
yield	76.62	76.18	84.63
API gravity		58.5	52.8
Octanes	Clear	+3cc tel.	Clear
Research	90.0	98.1	90.0
Motor	80.9	88.9	81.1

These data show that the step of cyclizing the paraffinic gasoline components is extremely effective in increasing the overall depentanized liquid yield when upgrading the octane number. Although the octane number of the raw raffinate can be increased to 90 RON clear without the cyclization step, the liquid yield is much lower — 76.1 vol.-% as against 83.2 vol.-% for the cyclized raffinate. Also of significance is the higher hydrogen yield when processing the precyclized raffinate.

What is claimed is:

1. A process for increasing the octane number of a paraffin containing gasoline blending component boiling within the gasoline boiling range and having a par-

affin content of from about 70 percent or higher which comprises the steps of (1) cyclizing the paraffins in the blending component by contacting said component under reforming conditions with hydrogen in the presence of a catalyst comprising a noble metal on magnesium oxide in an alumina gel matrix, to obtain a cyclized blending component, and (2) catalytically reforming said cyclized blending component in the presence of a conventional platinum or platinum bi-metallic reforming catalyst of an alumina or alumina containing support.

2. A process according to claim 1 in which the noble metal is platinum.

3. A process according to claim 1 in which the noble metal is palladium.

4. A process according to claim 2 in which magnesium oxide is impregnated with a solution of a soluble platinum compound and the impregnated powder is dried prior to its mixing into the alumina gel matrix.

5. A process according to claim 4 in which the platinum compound is chloroplatinic acid.

6. A process according to claim 1 in which the noble

metal is stabilized with another metal selected from Groups IV A, V B, VI B, VII B and VIII of the Periodic Table.

7. A process according to claim 1 in which the catalyst of step (1) is promoted with a halogen compound.

8. A process according to claim 1 in which the contacting takes place at a temperature of from about 500° to about 1,100°F. and a pressure of from about 50 to about 900 p.s.i.g.

9. A process according to claim 8 in which the temperature is from 700° to 1,000°F. and the pressure is from 50–500 p.s.i.g.
